UNITED STATES PATENT OFFICE

JAMES CAVANAGH, OF COHASSET, MASSACHUSETTS, ASSIGNOR TO UNITED SHOE MACHINERY CORPORATION, OF PATERSON, NEW JERSEY, A CORPORATION OF NEW JERSEY

HEEL

Application filed January 26, 1927, Serial No. 163,693. Renewed July 19, 1932.

This invention relates to improvements in the manufacture of shoes and is illustrated in connection with a wood heel.

In the manufacture of shoes to which wood heels are to be attached, it is usual to trim away the peripheral portion of the heel-seat of the sole of each shoe to an extent sufficient to permit the edge of the heel to engage directly upon the inturned edge of the material of the shoe upper. Usually this trimming of the heel-seat is done by a bevel cut extending around the periphery of the heel-seat and terminating at the heel breast line with a pair of shoulders, or some other suitable abutment, arranged to engage the breast of the heel. This trimming and beveling of the heel-seats of shoes is known as "heel-seat fitting".

After the heel-seat fitting operation, in order to solidify the heel-seats and to shape them more closely to conform to the attaching surfaces of the heels which are to be attached, the heel-seats of shoes have been sometimes molded under heavy pressure. The dies used for this purpose, while of the general shape of the attaching surfaces of the heels which are to be applied, have usually been somewhat smaller, so that the extreme edge of the heel from one breast corner around the rear and forward to the other breast corner, engages upon unmolded stock surrounding the molded portion. The unmolded portion thus acts as a cushion and yields somewhat in case of irregularities, thus facilitating the obtaining of a tight joint between the edge of the heel and the shoe upper.

It is an object of the present invention to provide an improved heel of a character that, even without the molding of the heel-seat by a die prior to the attachment of the heel, will insure an edge joint which will be tight not only when the shoe is new, but also after it has been worn for an extended period of time. As illustrated, this object is attained by forming the attaching surface of a wood heel so that the molding pressure which it can be caused to exert upon the heel-seat of a shoe during its attachment will be relieved at the edge of the heel-seat of the shoe, thus leaving an unmolded portion which will be

engaged by and will serve as a cushion for the edge of the heel. The edge of the heel, moreover, serves to hold or to assist in holding in place the leather or other material of the shoe upper which has been pulled in toward the center of the heel-seat by the molding action of the heel.

As wood heels have heretofore been made with a rather sharp rim at the edge of the attaching surface, there has been considerable breakage during the manufacture of the heels by reason of the weakness of this rim. Moreover, after the heels have been attached to shoes, this narrow rim has had a decided tendency to dig into the material of the shoe upper and counter, thereby weakening the shoe and injuring its appearance. It is, therefore, an object of the invention to provide a heel having a rim at the edge of its attaching surface of a character which will obviate these objections. Accordingly, the illustrated heel is provided with a rim of substantial width (for example, about one-tenth of an inch, more or less) arranged to bear upon the unmolded peripheral portion of the heel-seat of the shoe. The presence of such a comparatively wide rim at the edge of the heel, regardless of the form of the rest of the attaching surface, much reduces the number of heels spoiled during their manufacture and provides a better bearing than has heretofore been had between the shoe upper and the edge of the heel.

In accordance with another feature of the invention, the heel may be, and, as illustrated is, provided with a groove substantially parallel to the periphery of the heel and located between the molding portion of the attaching surface of the heel and the rim or edge of the attaching surface of the heel. This groove serves to relieve the molding pressure around the periphery of the heel and to catch and retain any adhesive that may be squeezed out as the pressure is applied.

In another aspect my invention relates to improvements in methods of manufacturing shoes in which one part is attached to another by means of an adhesive, characterized by the provision of a groove near and

approximately parallel to the edge of one of the parts which groove serves to trap any adhesive that is forced outwardly as pressure is applied to the shoe parts. Thus, as 5 illustrated herein, a groove extending peripherally of the attaching face of a heel serves to trap the heel attaching glue as it moves outwardly under the heel attaching pressure, thereby preventing the glue from soiling the 10 shoe upper. While the invention is illustrated herein with respect to the attachment of a heel to a shoe it should be understood that in various of its aspects the invention is not limited thereto.

15 With the above and other objects and features in view, the invention will now be described with reference to the accompanying drawing and pointed out in the claims.

In the drawing,

20 Fig. 1 is a perspective view of a wood heel embodying the present invention;

Fig. 2 is a cross-sectional view of a shoe after the performance of the heel-seat fitting operation and ready to have one of my 25 new heels attached;

Fig. 3 is a transverse section through the heel of Fig. 1; and

Fig. 4 is a transverse section through the heel-seat portion of a shoe with one of my 30 new heels attached thereto.

Fig. 1 illustrates a Cuban heel embodying the present invention. It should be understood, however, that the invention is equally applicable to heels of other styles.

35 The illustrated heel has an attaching surface shaped to relieve the pressure at the edge of the heel seat of the shoe as the heel is forced against the heel seat of the shoe while it is being attached. The major portion of the attaching surface of the heel is formed, as indicated at 6, to correspond approximately to the form to which the heel seat 8 of the shoe to which the heel is to be attached has been trimmed and to mold the 40 heel seat under the heel attaching pressure. Under present commercial conditions there is more or less variance in the shape to which the heel-seats of different shoes are trimmed, even though the shoes are intended to be identical and are to receive the same size and shape of heels. However, the heel seats of 45 shoes are sufficiently compressible so that they may be molded to substantial uniformity by an amount of pressure which it has been found to be practicable to apply through a wood heel in attaching the heel.

50 In order to provide a close or tight edge joint, the molding portion 6 of the attaching surface of the illustrated heel does not extend all the way to the edge (except at the breast of the heel), the molding portion being bounded by a groove 10, formed, as illustrated, semi-circular in cross-section and extending parallel to the periphery of the heel. 55 The portion 12 of the heel-seat of the shoe

immediately surrounding the portion engaged by the molding portion 6 of the attaching surface of the heel is not molded by the pressure of the heel to any substantial extent and thus serves as a cushion to receive a 70 wide peripheral rim 14 formed upon the heel beyond the groove 10, as shown in Fig. 4. The presence of this wide rim 14 not only provides a better bearing between the edge of the heel and the shoe upper, but also 75 strengthens the heel itself and much reduces the number of heels damaged during their manufacture by the breaking of their edges. As heretofore stated, this rim may be about one-tenth of an inch wide, more or less; in 80 any event it is preferably at least one-twentieth of the width of the attaching face of the heel, as illustrated in Fig. 3, and it may in some cases be even wider if the size of the shoe parts to which the heel is to be 85 attached will permit. As shown, the rim 14 is flat and, being of such great width relatively to the heel, provides safely and surely for a perfect bearing of the heel upon the 90 shoe upper. The groove 10, in addition to relieving the molding pressure at the periphery of the heel seat, acts also to catch any 95 glue or other adhesive, applied prior to the attachment of the heel to the shoe and squeezed out by the pressure of the heel, and thus prevents soiling the shoe upper.

In attaching a heel of this character to a shoe, the heel-seat fitting operation is performed in the normal way. Glue or other suitable adhesive is applied to the attaching 100 surface of the heel and, if desired, also to the heel-seat of the shoe. The heel is then properly positioned upon the heel-seat of the shoe and sufficient pressure is applied to cause the heel to mold and compress the heel-seat of the shoe, bringing substantially the whole of the molding portion 6 of the attaching surface of the heel into contact with the heel-seat of the shoe. The rim 14 of the heel at the same 105 time is brought into engagement with the overlusted upper about the periphery of the heel-seat constituting the unmolded marginal portion 12 of the heel-seat of the shoe, the latter yielding, if necessary, to compensate for any unevenness or irregularities that 110 may be present. This molding action of the heel tends to pull the leather or other material of the shoe upper inwardly around the edge of the heel-seat of the shoe and the pressure of the rim 14 holds or assists in holding 115 the material of the shoe upper in the position it thus assumes. Later, usually after the adhesive has set, nails are inserted through the heel-seat of the shoe into the heel to supplement the adhesive as a means for retaining 120 the heel in place.

125 It should be also noted that the groove 10 serves as a reservoir, trapping and holding any surplus glue which may be squeezed outwardly as the pressure is applied, thereby pre- 130

venting the glue from soiling the visible portion of the shoe upper.

It should be understood that the comparatively wide rim surrounding the attaching 5 surface of the heel is not limited in its utility to heels having the remainder of their attaching surfaces of the form herein illustrated or provided with a groove located between the rim and the central portion of the attaching 10 surface of the heel. Moreover, while in the illustrated heel all parts of the flat rim 14 lie in the same plane, it is not essential that this be so.

Having fully described my invention, what 15 I claim as new and desire to secure by Letters Patent of the United States is:

1. A wood heel having its attaching surface bounded by a flat rim of substantial width and having a groove substantially parallel 20 to the periphery of the heel and forming an inner boundary for said rim, the portion of the attaching surface bounded by the inner margin of said groove being concave and having its periphery substantially on a 25 level with said flat rim.

2. A wood heel having a concave attaching surface surrounded by a groove, with a rim of substantial width beyond the groove.

3. A wood heel having on its attaching face 30 a concave surface to receive the end of a heel-seat-fitted sole, said surface being surrounded by a groove of rounded cross-section and having an upper engaging rim beyond and above said groove.

35 4. A wood heel having its attaching surface provided with a glue-retaining groove adjacent to and substantially parallel with the periphery of the attaching surface of the heel, said groove serving to disrupt the continuity 40 of the engaging surfaces of the heel and shoe and to prevent glue from exuding from the joint between the shoe and heel.

5. That improvement in methods of manufacturing shoes in which one part is secured 45 to another with an adhesive which comprises providing a groove spaced from but near the edge of one of the surfaces of the parts which are to be attached, applying adhesive to and assembling the parts, and applying pressure 50 whereby adhesive which is forced outwardly between the parts is trapped in the groove.

6. That improvement in methods of securing a shoe bottom member to a shoe with an adhesive under pressure characterized by the 55 forming in the shoe bottom part of a groove extending peripherally thereof and trapping in the groove such adhesive as is squeezed outwardly under the pressure applied to the shoe parts.

60 7. That improvement in methods of manufacturing shoes which comprises forming a groove adjacent to and substantially peripherally of the attaching face of a heel, applying the heel to a shoe with a layer of adhesive 65 between the two and pressing the heel upon

the shoe while the glue is setting, and trapping in the groove such glue as is forced outwardly between the heel and the shoe bottom.

In testimony whereof I have signed my name to this specification.

JAMES CAVANAGH.
